UNITED STATES PATENT OFFICE.

JAMES McG. McCULLOCH, OF GARSTON, COUNTY OF LANCASTER, ENGLAND.

STEAM-BOILER.

SPECIFICATION forming part of Letters Patent No. 313,944, dated March 17, 1885.

Application filed September 8, 1884. (No model.) Patented in England August 19, 1884, No. 11,414.

To all whom it may concern:

Be it known that I, JAMES McGOWAN McCULLOCH, a subject of the Queen of Great Britain, residing at Garston, in the county of 5 Lancaster and Kingdom of England, have invented certain new and useful Improvements in Steam-Boilers, for which I have applied for Letters Patent in England dated August 19, 1884, No. 11,414.

10 This invention has for its object a boiler with very large and effective heating-surface, easy of construction and of repair, and with good circulation.

Referring to the drawings, Figures 1 and 2 15 are transverse and longitudinal sections of a boiler with two furnaces; Figs. 3 and 4, longitudinal and transverse sections showing a modification applicable where there is only one furnace and one return-flue; Fig. 5, a modification showing one furnace and two return-flues; Fig. 6, an enlarged view showing a conical flue with cylindrical ends.

The invention consists, essentially, first, in a furnace flue or flues extending the full 25 length of the boiler, and in height from the bottom or from near the bottom of the boiler to a little below the minimum water-level of the boiler; second, in piercing the upper portion of this flue or flues with a series of trans- 30 verse slightly-inclined and preferably conical water-tubes; third, in bringing the return flue or flues back alongside the furnace-flue, but below the level of the water-tubes in the furnace-flue; fourth, in placing a series of pref- 35 erably conical vertical or nearly vertical wa- ter-tubes through this return-tube.

Referring to the drawings, in which like letters refer to like parts throughout, A is the boiler-shell, preferably circular, but other 40 forms, if well stayed, could be used; B, fur- nace-flue, preferably round-topped when space admits of it, as in Figs. 1 and 2; but in the case of small boilers, where it would reduce the available number of transverse tubes too 45 much, I make it flat-topped, or nearly so, and well stayed; C, fire-bars of any ordinary con- struction; D, bridge; E, transverse tubes, pref- erably conical, with bottom surface about 50 level; but where parallel tubes are used I in- cline them upward somewhat toward the space over the return-flue. I prefer to so design the

boiler that at even the small ends of all tubes there shall be a vacancy beyond of about eighteen inches in breadth to enable a man to go in and calk or unscrew or tighten them. 55 The tubes I prefer to form with a thread screwed into each tube-plate, and having a nut or nuts at each end to still further hold the tube and make a tight joint. If nuts be used, the tubes should be parallel where they 60 enter the tube-plate, and a little on each side, so as to give the nuts fair play. The tubes thus act as stays, even though conical. F, back end common to all flues; G, return-flue. The partition between the furnace and return- 65 flue can be a simple plate, preferably incased in fire-clay, a fire-brick wall, or a thin feed-wa- ter-heating space. It is of course omitted altogether at F. It is shown entirely removed in the longitudinal view. In some cases I 70 may, however, join the flues outside the boiler. H, vertical tubes, preferably conical, and screwed at each end into the tube-plates, as above-described; I, space sufficiently wide and deep to enable a repairer to withdraw the 75 tubes through it; J, water-space at small or lower end of tubes, preferably about eighteen inches wide, for working in; K, man-hole; L, staying devices to prevent collapse of flue; M, water-chamber attached externally to back 80 end of flue, forming a feed-heater and chest, where any sediment from the feed-water may collect. Not being a vital part of the boiler, the chest can be renewed at small cost. The object is, further, to prevent overheating of 85 the back plate.

I am aware that a conical or tapering wa- ter-tube threaded at its ends is not broadly new; but, so far as I am aware, such threaded ends have never before been made cylindrical 90 on the exterior, but have, instead, had the same taper as the body of the tube.

I am also aware that a feed-water heater has been attached to the rear end of a boiler hav- 95 ing a furnace-flue and return-flue united at the back end; but in that case only a portion of the end plate was thus protected, a removable door being made to close and form a consid- erable portion of each end.

I claim as my invention—

1. A steam-boiler having a forward and re- 100 turn flue opening into each other at the one

end, but separated from each other by a thin partition except at that end, and each pierced with transverse tubes at right angles, or nearly so, to those of the other.

5. 2. The combination of a furnace-flue having transverse tubes in its upper part, with a return-flue alongside but not sufficiently high to interfere with the replacing of the transverse tubes, substantially as described.

10. 3. In a boiler, a longitudinal furnace-flue having a series of transverse tubes in its upper part, in combination with a longitudinal return-flue of less height than the lowest part of the tubes of the furnace-flue, and fitted 15 with vertical water-tubes, substantially as described.

4. In a boiler, a water-space, I, having two or more of its sides formed by flues pierced with water-tubes opening into said space, the 20 width of the clear space in front of the tubes being greater than the length of said tubes, whereby the tubes can be withdrawn into said space when required, and the steam escaping

from said tubes will have free opportunity to escape, substantially as described.

5. In combination with a boiler having a main furnace-flue and a return-flue united at the back end, a feed-water chamber attached to and covering the entire rear end, whereby the end plate is completely protected against the fire and a large heating-surface is secured for the feed-water chamber.

6. A steam-boiler having a primary furnace-flue of substantially square section, from adjacent sides of which project the tubulous return-flue spaces, and open freely to the primary flue, and each projecting flue-space having its tubes opening out into the rectangle formed by the two projections.

In testimony whereof I have signed my name 40 to this specification in the presence of two subscribing witnesses.

JAMES M. McCULLOCH.
